UNITED STATES PATENT OFFICE.

EUGENE D. JEFFERSON, OF LOWELL, MASSACHUSETTS.

BLEACHING APPARATUS.

1,044,185.

Specification of Letters Patent. Patented Nov. 12, 1912.

Application filed May 1, 1908. Serial No. 430,335.

To all whom it may concern:

Be it known that I, EUGENE D. JEFFERSON, a citizen of the United States, residing at Lowell, in the county of Middlesex and 5 State of Massachusetts, have invented certain new and useful Improvements in Bleaching Apparatus; and I do hereby declare the following to be a full, clear, and exact description of the invention, such as will enable others skilled in the art to which it 10 pertains to make and use the same.

The present invention relates to an improvement in bleaching apparatus, particularly adapted for the bleaching of cotton 15 fabrics.

The object of the invention is to reorganize and improve the apparatus of my former Patent No. 775,450, granted Nov. 22, 1904, and especially to adapt it to carry out 20 the method of my patent for method of bleaching cloth No. 992,133, granted May 9, 1911.

The invention consists in the apparatus 25 hereinafter described and particularly defined in the claims.

In the accompanying drawings illustrating the preferred form of apparatus, Figure 1 is an elevation partially in section, and Figs. 2 and 3 are respectively an elevation 30 and a plan of the motive fluid valve operating mechanism.

The keir proper 1 consists of a large vessel provided near its bottom with a grid or grating 70; and at its top with a man-hole 35 through which the cloths to be treated are introduced and removed. The cover of the man-hole is not shown. Connected with the bottom of the keir is a pipe 2 which may be called the bottom pipe. It is provided with 40 a check valve 3 which opens away from the keir. The bottom-pipe 2 is connected at the cross 4 with the draw-off pipe, with the trap or well 8, and with the top of the keir. The draw-off pipe 5, by means of which the 45 keir may be emptied, is provided with a draw-off valve 6. The pipe 7 leads from the cross 4 to the trap or well. The pipe 9 leads from the cross 4 to the top of the keir, being provided with the injector check- 50 valve 10 near its point of entrance into the keir and at its discharge end in the keir with the spray head 11. The pipes 2, 7 and 9 constitute the vomiting pipe through which liquor is conveyed from the bottom of the keir to the top and vomited in upon the 55 fabric. The keir is provided with a test cock 12 located in its side at what for convenience will be termed the "normal level" and which is the level at which the operator desires to have the liquor in performing certain operations. The keir is also provided with a series of overflow openings at 13 through which the liquor may flow under certain conditions of use. The liquor flows from these openings into an overflow chamber 14, and a pipe 15 is provided to carry away the liquor, a cock 16 affording means for closing this pipe. This provision of 60 openings for overflow it will be convenient to refer to as the "washing overflow". At the top of the keir a filling overflow and vent pipe 17 is provided, having a cock 18 for closing the same when desired. Here also is provided a safety valve 19 and a pressure gage 20. A filling pipe 21 is connected with a T in the bottom-pipe 2, and affords means for introducing liquors into 65 the keir. The water admission pipe 22 is connected with this filling pipe 21. So also the chemic pipe 23 and acid pipe 24. These 70 pipes are provided with valves which may conveniently be referred to respectively as the water supply valve, chemic supply valve and acid supply valve. The trap or well 8 constitutes part of the apparatus for causing 75 the liquor to be withdrawn from the bottom of the keir and vomited intermittently into the top. It comprises a tank into which the liquor from the keir flows through the pipes 2 and 7. When the liquor rises 80 in the trap 8 to about the level A, the liquor rising in the pipe 25 enters the pipe 26 which leads to the motive fluid valve operating mechanism, indicated in a general way by the reference character 0. The trap 8 85 is provided with a passageway pipe 27 which is secured at each end in the opposite walls of the trap. It therefore provides a passageway for the pipe 25 to the regulator. The fact that it passes through the trap is 90 of significance only as affording a compact construction. The pipe 25 connects with the regulator at 28, and the liquor passes thence through the lower ball-pipe 29 to the ball 95 30. The ball 30 is provided with an upper ball-pipe 31 which leads back to the 100 105

T 32 and thence through the pipe 33 to the pivot casting 34 to which the pipe 35 is connected at 36. The pipe 35 passes through a passageway pipe 37 in the 5 same manner as the pipe 25. The pivot casting 34 is mounted upon a stud 38 secured to the trap 8. The pipes 29, 31 and 33, the ball 30, and the pivot casting 34 constitute a frame which is pivotally mounted at 38 and capable of oscillating about such pivot. A counter-weight 39 on the arm 40 which is secured to the pivot casting affords means for lifting the ball 30 when it is emptied. From the T 32 extends upward a pipe 41 10 which is connected by means of a link 42 with a motive fluid valve 43. The upper end of the pipe 41 is connected by the air pipes 44 and 45 with the injector check 71 above the check valve 10.

15 The pipes 44 and 45 afford a vent for the ball 30 while the liquor is flowing into it. They also afford communication between the ball and the top of the keir when the level of the liquor falls in the trap 8 below 20 the level of the ball so as to permit the liquor to run out of the ball. It is to be observed that with this motive fluid valve regulating apparatus the pipes 25, 35 and 44 yield, owing to their elasticity, and the 25 use of stuffing glands and the like is avoided.

20 The motive fluid supply pipe 46 leads to the motive fluid valve 43 and the pipe 47 leads from the motive fluid valve 43 to the top of the trap or well 8. The pipe 46 conveniently leads to the injector nozzle of the 30 injector check valve 10 and is provided with two valves 48 and 49 respectively below and above the steam and air pipe junction therewith. This steam and air pipe 50 is connected with a steam supply pipe 51, provided with a steam supply valve 52, and an air supply pipe 53, provided with an air supply valve 54.

35 The opening of the air valve 54 permits air to flow down through the pipe 46, pipe 47, check 55 and pipe 56, into the top of the trap, thereby forcing the contents of the trap out through the pipe 7 and up through the pipe 9 into the top of the keir. The 40 check valve 55 consists of a casting provided with a ball 55^a adapted to engage upper and lower valve seats. When the motive fluid is vomiting the contents of the trap or well into the top of the keir, the ball 55^a will 45 be held against its upper seat and the communication afforded by the pipes 44 and 45 between the ball 30 and the top of the keir will not be disturbed by the passage of motive fluid into these pipes. Moreover, the 50 loss of motive fluid flowing through this small pipe to the top of the keir is by this means prevented. When the motive fluid is cut off, the ball 55^a falls against its lower seat and permits the pipe 45 to vent the 55 trap or well to the top of the keir, thereby

affording a free admission of the liquor to the trap. The brace or strut 57, conveniently made of piping, is a support for the pipes 46 and 47, but it affords no communication between the pipe 47 and the trap 8.

70 The apparatus above described may be used as follows:—The fabric is run into the keir and trodden down in the usual way, after which the chains 72 are put in place and the manhole is closed. Thereupon the boiling operations are performed substantially as described in said patent. For convenience the whole series of operations of boiling and bleaching with the present apparatus will be described in detail. It is as 75 follows:—First, caustic liquor is introduced through the pipe 21 and brought to a proper level in the keir. The pressures in the top and bottom of the keir are maintained in 80 equilibrium through the connection afforded by the pipes 45 and 56, so that, as the liquor rises in the keir, the liquor will flow through the pipes 2 and 7, and the check valve 3 into the trap 8 and will rise in the trap until it reaches the level A, when it will flow into 85 the ball 30 and cause the ball to fall, thereby opening the valve 43. After a sufficient amount of caustic liquor is introduced into the keir, the valve admitting the caustic liquor is closed, the cock 49 is closed, the cock 48 is opened, and the steam cock 52 is opened, admitting steam from the steam pipe 51 into the pipe 46. The steam will flow through the pipe 46, through the valve 43 (which is now held open by the falling of the ball 30), 90 through the pipe 47, through the check valve 55, and through the pipe 56, into the top of the trap 8. The pressure of the steam will force the ball 55^a of the check valve 55 against its upper seat, thereby closing the 95 passage between the vent pipe 45 and the top of the keir, and the steam will force the liquor in the trap out through the pipe 4, thereby closing the check valve 3, and the 100 liquor will then flow up through the pipe 9 and be vomited into the top of the keir. The 105 passages through the pipes 29 and 31 are small enough so that the liquor will flow slowly out of the ball 30 and the steam will have forced nearly all of the liquor out 110 of the trap 8 before the ball 30 is drained of its contained liquor. The empty ball 30 will be overbalanced by its counterweight 39 and will therefore rise when the trap 8 is emptied of its liquor, the valve 43 will 115 thereby be closed, the steam will be cut off from the trap 8, and the connection will be reestablished between the top and bottom of the keir through the pipes 45 and 56, owing to the fall of the ball in the check valve 55; 120 the liquor will then gradually flow out of the keir through the pipes 2 and 4 into the trap 8 until it reaches the level A, whereupon the liquor will again fill the ball 30 which will fall and open the valve 43, admitting the 125 130

steam, and the operations will thus automatically continue. This boiling operation will be continued from seven to ten hours.

At the completion of the boiling operation 5 the washing process is performed. First, the caustic liquor is drawn off through the draw-off pipe 5. Clean water is then run in from the water admission pipe through the filling pipe 21, and allowed to flow 10 through the fabric and out through the washing overflow pipe 15, the valve 16 being opened for this purpose. This washing process will be continued for about an hour and a half. The time of washing will depend somewhat upon the pressure of water 15 used, as with higher pressures more water will be passed through the cloth in a given length of time than with lower pressures. At this stage, according to the old methods 20 of bleaching, the cloth would be ready to be removed from the keir, but according to the present invention, and in the practice of my improved method of bleaching, the bleaching will now be begun without removal 25 of the cloth from the keir.

The washing process having been completed to the extent usual in the washing of goods after the caustic or boiling operation, the water admission valve is closed, and 30 the washing overflow valve 16 is closed, and the draw-off valve 6 is opened, and the water is drawn down to the normal level. This will be ascertained by opening the test valve when the draw-off valve is opened; then the 35 cessation of the flow of water therefrom indicates that the normal level has been reached. The final washing of the cloth, preparatory to the bleaching process, is now accomplished by closing the valve 49, opening 40 the valve 48, and opening the compressed air valve 54 which admits compressed air to the apparatus. The operation of the apparatus when operated by compressed air differs from its operation when operated by 45 steam, in that while in the operation by steam the condensation of the steam keeps the liquor hot and secures the intermittent or vomiting operation of the apparatus, when operated by compressed air the air 50 will blow the water from the trap 8 into the top of the keir until it blows air out through the relief or safety valve 19, by which time the ball 30 will have fallen, and the valve 43 will have been closed, thereby 55 reestablishing communication between the top and bottom of the keir, and permitting the water to flow out of the bottom of the keir into the trap. This washing or scouring operation is continued for about an hour, 60 to remove the last traces of caustic from the fabric. The compressed air is now shut off, and clean water is again run into the keir, driving out the water which has been used through the washing overflow as before.

The water is now drawn off from the keir. 65 This is conveniently accomplished by opening the draw-off valve 6 to allow the water to flow out at the bottom, and at the same time opening the cock 49, closing the cock 48, and opening the compressed air valve 54, 70 so that the compressed air being forced into the top of the keir drives the water out at the bottom. The fabric is now ready for the chemic. Chemic is now run into the keir from the chemic tank through the chemic 75 pipe 23, until the level of the chemic in the keir rises to the normal level. The supply of chemic liquor is then cut off, and the compressed air is turned on, and the cloth is subjected to the operation of the chemic 80 liquor, which is drawn out at the bottom and vomited in at the top for about five hours. A peculiar operation of the apparatus during this operation under compressed air and with a limited amount of 85 liquor in the keir arises from the fact that the cloth opens up when the liquor level rises, and closes down as it falls, thereby causing the chemic to flow into the interstices between the cloth, and to be squeezed 90 out of such interstices again, as a result of which a very thorough and effective contact of the chemic with all parts of the cloth is secured. In this connection it is to be observed that the chemic when it is vomited 95 into the keir is thoroughly aerated by passage through the compressed air which is being expelled by the entering liquid. This aeration of the chemic enables the operation to be performed in a closed keir. At the 100 completion of the chemic operation, the chemic is blown back into the chemic tank, or into another keir that may be ready to receive it. This leaves the cloth saturated with air. This is of advantage, as it secures 105 the thorough aeration of the cloth. The fabric is then subjected to a washing operation such as has been hereinbefore described, for about one and one half to two hours under ordinary circumstances, after which 110 the water is drawn off, and the acid pipe is opened and the acid is run into the keir up to the normal level, and the air is turned on, and the scouring operation as before described is again repeated. This scouring 115 operation is continued for about two hours. Then the acid is blown back into the acid tank, or into another keir ready to receive it. The bleaching operations having been completed, the goods are again washed with 120 water for about two hours. The cloth is then ready for starching and the cloth is, therefore, run out of the keir preparatory to the starching, and inasmuch as it will not occupy any additional time, it may be 125 found convenient to run it through a washing machine before running it into the bin ready for the starching machine.

The use of compressed air as the motive fluid for moving the treating liquors is of advantage over steam for certain purposes, inasmuch as it permits the operation of the liquors at any desired low temperature.

The method of bleaching, described herein for the purpose of elucidating modes of use of the apparatus, forms the subject of my patent above referred to, Ser. No. 992,133.

10 Having thus described the invention, what is claimed is:—

1. An apparatus for treating textiles consisting of a closed keir and vomiting pipe connecting the top and bottom of the keir, 15 a trap or well connected with the vomiting pipe, a motive fluid supply pipe connected with the trap, a valve in said pipe, and valve operating mechanism comprising a hollow ball, ball lever, and pipe connections 20 between the ball and the trap and between the ball and the top of the keir operating automatically to open the valve when the level of the liquor in the trap reaches a predetermined height, and to close the valve 25 when the ball is emptied of its contained liquor, substantially as described.

2. An apparatus for treating textiles, having, in combination, a keir, a vomiting pipe connecting the bottom and top of the keir, 30 a trap or well connected with the vomiting pipe near the bottom thereof, a motive fluid supply pipe connected with the trap, a valve in said supply pipe, a pivoted lever connected to said valve and having a hollow ball on one end and a weight on the other end, pipe connections with the ball connected to the top of the keir and to the lever near the pivot thereof and of a length sufficient to permit their springing to compensate for movements of the lever, and pipe connections between the ball lever and the trap, substantially as described.

3. An apparatus for treating textiles, having, in combination, a keir, a vomiting pipe 45 connecting the bottom and top of the keir, a trap or well connected with the vomiting pipe and near the bottom thereof, a motive fluid supply pipe connected with the trap, a valve in said supply pipe, a ball lever connected to said valve consisting of piping having a hollow ball on one end and a weight on the other end, pipe connections between the ball lever and the top of the keir of such length as to permit oscillations 55 of the ball lever by the elasticity of the pipe connections, and pipe connections between the ball lever and the trap, substantially as described.

4. An apparatus for treating textiles, having, in combination, a closed keir, a vomiting pipe connecting the top and bottom of the keir, a trap connected with the vomiting pipe, valve mechanism for controlling the

vomiting comprising a valve operating lever, a valve and connections between the valve and the lever, said valve operating lever supporting a hollow ball at one end and having pipe connections from the top and bottom of the ball to a pivot casting upon which the lever is pivoted, and a vent pipe connected with the top of the keir extending from the upper pipe connections with the ball and pipe connections to the lever rigidly connected with the pivot casting and of such length as to permit oscillations of the lever of sufficient amplitude to operate the valve by the yielding of the pipe connections, substantially as described.

5. An apparatus for treating textiles, having, in combination, a keir, a vomiting pipe connecting the top and bottom of the keir, a trap or well connected with the pipe near the bottom thereof, said pipe being provided with a check valve opening away from the keir and toward the trap or well, a filling pipe entering the vomiting pipe near the keir, a check valve in the vomiting pipe near the top of the keir opening toward the keir, an injector located in the vomiting pipe near the top of the keir, a motive fluid supply pipe connected with the injector and with the trap or well, and means for controlling the flow of the motive fluid substantially as described.

6. An apparatus for treating textiles, having, in combination, a keir, a vomiting pipe connecting the bottom and the top of the keir, a trap connected with the vomiting pipe, means for raising the liquor from the trap through the vomiting pipe from the bottom to the top of the keir, automatic means actuated by the rise and fall of the liquor level in a part of the said apparatus for controlling the operation of said liquor raising means, and a vent connecting the trap and the top of the keir, substantially as described.

7. An apparatus for treating textiles, having, in combination, a keir, a vomiting pipe connecting the bottom and the top of the keir, a motive fluid supply pipe connected with the vomiting pipe, a valve in said supply pipe, valve operating mechanism comprising a hollow ball, ball lever and pipe connections between the ball and the vomiting pipe, and a vent pipe connecting the ball and the top of the keir, substantially as described.

8. An apparatus for treating textiles, having, in combination, a keir, a vomiting pipe connecting the bottom and the top of the keir, a trap or well connected with the vomiting pipe near the bottom thereof, a motive fluid supply pipe connected with the trap, a valve in said supply pipe, and valve operating mechanism comprising a hollow ball,

ball lever and pipe connections between the ball and the trap and between the ball and top of the keir, substantially as described.

9. An apparatus for treating textiles, having, in combination, a keir, a vomiting pipe connecting the bottom and the top of the keir, a trap connected with the vomiting pipe near the bottom thereof, a motive fluid supply pipe connected with the trap, a valve in 5 said supply pipe, valve operating mechanism comprising a hollow ball and pipe connections between the ball and the trap, and a vent pipe connecting the ball and the trap with the top of the keir, substantially as described.

10. An apparatus for treating textiles, having, in combination, a keir, a vomiting pipe connecting the bottom and the top of the keir, a trap connected with the vomiting pipe, means for raising the liquor from 20 the trap through the vomiting pipe from the bottom to the top of the keir, automatic means actuated by the rise and fall of the liquor level in a part of the said apparatus 25 for controlling the operation of said liquor raising means, a vent connecting the trap and top of the keir, and a valve acting automatically to close said vent while the liquor is being raised from the trap to the 30 top of the keir, substantially as described.

11. An apparatus for treating textiles, having, in combination, a keir, a vomiting pipe connecting the bottom and the top of the keir, a trap connected with the vomiting 35 pipe and adapted to receive the liquor from the bottom of the keir, means for admitting a motive fluid into the trap to force the liquor from the trap through the vomiting pipe into the top of the keir, a vent for the 40 trap, and a valve acting automatically to close said vent while the liquor is being forced from the trap into the top of the keir, substantially as described.

12. An apparatus for treating textiles, 45 having, in combination, a keir, a vomiting pipe connecting the bottom and the top of the keir, a trap or well connected with the vomiting pipe near the bottom thereof, a check valve in the vomiting pipe between 50 the bottom of the keir and the trap and opening toward the trap to allow liquor to pass from the bottom of the keir into the trap, means for admitting a motive fluid into the trap to force the liquor from the 55 trap through the vomiting pipe into the top of the keir, a vent for the trap and a valve acting automatically to close the vent while the motive fluid is forcing the liquor from the trap into the top of the keir and a 60 valve to open the vent while the liquor is passing from the bottom of the keir into the trap, substantially as described.

13. An apparatus for treating textiles, having, in combination, a keir, a vomiting

pipe connecting the bottom and the top 65 of the keir, a well or trap connected with the vomiting pipe and adapted to receive the liquor from the bottom of the keir, a motive fluid supply pipe connected with the trap, a valve in said supply pipe, a valve operating mechanism comprising a hollow ball, a vent for the ball, a pipe connection extending from the bottom of the ball to the trap, a second pipe connection extending from 70 the top of the ball to a point in the trap between the top of the trap and the connection of the first pipe thereto, whereby liquor which flows into the ball when the trap is full is retained in the ball until the liquor level in the trap has dropped below the 75 point at which the second pipe connection enters the trap, substantially as described.

14. An apparatus for treating textiles, having, in combination, a closed keir, a vomiting pipe connecting the bottom and 85 top of the keir, means operated by compressed air for intermittently vomiting the liquor through the vomiting pipe from the bottom to the top of the keir, and means acting automatically for maintaining the 90 air pressure in the keir and for allowing the air displaced by the liquor vomited into the top of the keir to escape, substantially as described.

15. An apparatus for treating textiles, 95 having, in combination, a closed keir, a vomiting pipe connecting the bottom and the top of the keir, a trap connected to the vomiting pipe, means acting automatically for introducing compressed air into the 100 trap to intermittently force the liquor from the trap through the vomiting pipe into the top of the keir, and means acting automatically for maintaining the air pressure in the keir and for allowing the air displaced by the liquor vomited into the top 105 of the keir to escape, substantially as described.

16. An apparatus for bleaching textiles, 110 having, in combination, a closed keir, a vomiting pipe connecting the bottom and the top of the keir, a trap connected with the vomiting pipe, means for raising the bleaching liquor from the trap through the vomiting pipe from the bottom to the top of the 115 keir, automatic means actuated by the rise and fall of the liquor level in a part of said apparatus for controlling the operation of said liquor raising means, and means for subsequently blowing air through the 120 textiles in the keir to thoroughly aerate them, substantially as described.

17. An apparatus for bleaching textiles, 125 having, in combination, a closed keir, a vomiting pipe connecting the bottom and the top of the keir, a trap connected with the vomiting pipe, means for raising the bleaching liquor from the trap through the vomiting

pipe from the bottom to the top of the keir, automatic means actuated by the rise and fall of the liquor level in a part of said apparatus for controlling the operation of said liquor raising means, and means for forcing compressed air into the top of the keir and down through the textiles to blow out the liquor from the bottom of the keir and to

thoroughly aerate the textiles by saturating them with air, substantially as described. 10

In testimony whereof I affix my signature, in presence of two witnesses.
